UNITED STATES PATENT OFFICE.

JOHN SCOTT-TAGGART, OF LONDON, ENGLAND.

APPARATUS FOR DETECTING OR TRANSLATING ELECTRICAL IMPULSES.

Application filed April 30, 1921, Serial No. 465,731, and in Great Britain May 20, 1920.

This invention relates to the detection or translation of electrical impulses, and by translation is meant the production of local effects consequent upon the presence or reception of electrical impulses emanating from an external source, which effects are not normally or merely dependent upon the received impulses for their strength or power, although they are in general influenced in their character by the received impulses.

In the method involved in the present invention the frequency of the output signal varies with the intensity of the received impulses which produce a change in the interaction of the two sets of continuous electrical oscillations, resulting in the production in a suitable indicator of beats or of a change of frequency of existing beats. In the application of the invention to wireless signalling there are produced locally two sets of continuous electrical oscillations which are arranged to interact on each other so as to produce beats when their frequencies differ. Normally the local circuits are so adjusted and arranged with respect to each other and to a local indicator or detector that no effect is produced on the latter in the absence of electrical impulses emanating from an external source, although alternatively the circuits might be so adjusted as to produce a beat of a definite frequency under such circumstances. In either case, means are provided whereby the reception of external impulses so affects one or both of the local circuits as to cause a change in their interaction which produces an indication in the detector, e. g. by the production of beats or of a change of frequency in existing beats.

In the accompanying drawings Fig. 1 illustrates one method of carrying the invention into effect and Fig. 2 an arrangement in which a variable resistance in the form of a three-electrode thermionic valve is employed. I propose to use for this purpose a device responsive to changes in frequency of the type described in British patent specification No. 166,189. Two such devices A and B, comprising three-electrode valves V^1 , V^2 and associated circuits producing continuous oscillations, are so arranged that beats are produced through the interaction of the two sets of oscillations, these beats being rectified by one of the valves and giving audible signals in the telephone receiver T.

If now the frequencies are balanced so that no audible beats are produced, a variation of either frequency will upset the balance and give a note in the telephones. This change of frequency is effected by the incoming signals producing a variation of one of the electrical constants or factors of one of the continuously oscillating circuits, as for example a variation of a resistance inserted in one of the devices A, B across the oscillatory circuit L^1 , C^1 , which resistance is varied by the incoming signal.

Fig. 2 illustrates the use of a three-electrode valve V^0 as a variable resistance across the grid oscillatory circuit L^1 , C^1 of an oscillatory valve V^1 . The anode circuit of this valve contains a retroactor coil L^3 as commonly used. The valve V^2 is also arranged to produce oscillations of a frequency determined by the condenser C^2 and inductance L^2 , a retroactor coil L^4 and telephones T being included in the anode circuits. The filaments of the valves obtain their current from the battery B and the anode battery is represented by H. The frequency of the oscillations produced by V^1 may be varied by altering the conductivity of the valve V^0 by altering its grid potential. The normal adjustment of this grid potential may be varied by the potentiometer R which thus serves as a means of adjusting accurately the balance of frequencies. The input potentials are applied to the terminals X, Y.

Such a circuit may be adjusted so that normally nothing is heard in the telephones. Incoming potentials applied to X, Y will upset the balance of frequencies and give an audible signal in T or other indicator.

If desired, the incoming signal may be used to alter the frequency of an existing beat note.

It will be seen that a strong impulse applied to X, Y will cause such a change in one of the frequencies that the beats are beyond the audible limit. A limiting effect is thus obtainable.

If desired, the apparatus may be adjusted so that normally the beats are beyond the audible limit, but are brought into the audible limit by the input signal.

The apparatus may be used for a very large number of purposes where it is desired to produce a local output of a frequency dependent on the input strength. It may be used in telegraphy for producing a buzzing

note by the application of direct current potentials. It may be used for the reception of continuous waves, the rectified oscillations being led to the terminals X, Y.

5 It is desirable in this invention that the frequencies used be of a high order, say 1,000,000, in order that small input potentials may affect the balance of frequencies more readily.

10 The apparatus is especially useful when it is desired to compare the strength of impulses, as in wireless direction finding.

In a further modification the beat currents obtained from the device as hereinbefore described are arranged to interact with locally produced alternations of a different frequency so as to produce beats, these secondary beats being used to operate the indicator. With such an arrangement the 20 primary beats may be beyond audible frequency.

Having thus described the nature of the said invention and the best means I know of carrying the same into practical effect, I 25 claim:—

1. A method of translating or detecting electrical impulses, wherein the received impulses produce variations in a resistance with consequential change in the interaction 30 of two sets of independently produced continuous electrical oscillations, said change producing in a suitable indicator beats or a change of frequency of existing beats.

2. An apparatus for translating or detect-

ing electrical impulses, comprising two electrical oscillation generators having circuits arranged to interact with each other, an indicator associated therewith and adapted to give indications when the frequencies of the oscillation generators differ, and means responsive to received electrical impulses operating to vary a resistance associated with one of the oscillating circuits.

3. An apparatus according to claim 2, wherein the received impulses vary the resistance of a three-electrode valve shunted across one of the oscillating circuits.

4. An apparatus according to claim 2, wherein the received impulses vary the grid potential and consequently the resistance of 50 a three-electrode valve shunted across one of the oscillating circuits.

5. An apparatus for translating or detecting electrical impulses, comprising a pair of electrical oscillation generators having circuits arranged to interact with one another, an indicator associated with said circuits and adapted to show when the frequencies of said generators differ, a three-electrode valve shunted across one of said oscillating circuits and of which the grid potential, and consequently the resistance, is varied by the received electrical impulses, and a local potentiometer device for varying the initial grid potential of said three-electrode valve.

In testimony whereof I have signed my name to this specification.

JOHN SCOTT-TAGGART.
